UNITED STATES PATENT OFFICE.

MICHAEL MAREA AND THOMAS CONNORS, OF GARRETT, INDIANA.

VALVE.

SPECIFICATION forming part of Letters Patent No. 593,594, dated November 16, 1897.

Application filed September 16, 1896. Serial No. 606,019. (No model.)

To all whom it may concern:

Be it known that we, MICHAEL MAREA and THOMAS CONNORS, citizens of the United States, residing at Garrett, in the county of 5 De Kalb, State of Indiana, have invented certain new and useful Improvements in Valves, of which the following is a specification, reference being had therein to the accompanying drawings.

10 This invention relates to certain new and useful improvements in valves designed for water-raising systems for sleeping-car service and the like; and it has for its objects, among others, to provide a simple and cheap construction of valve designed for attachment to the car and for connection with the train-line or main train-pipe that supplies the air for the brakes on the train. While it is designed primarily for this purpose, it will be seen that 15 it is adapted for use in all places where a supply-valve is needed, where the pressure is supplied and the reduction is made, and the valve is designed to work automatically to hold the pressure that has already been ac- 20 cumulated in the reservoir, being normally held open, so as to admit the air from the service-pipe to the reservoir, but automatically closing when there is a reduction in the pressure in the supply-pipe, and thus retain in 25 the reservoir the pressure that has been there- 30 in accumulated.

Other objects and advantages of the invention will hereinafter appear in the following description, and the novel features thereof 35 will be more particularly pointed out in the appended claims.

The invention is clearly illustrated in the accompanying drawings, which, with the letters of reference marked thereon, form a part 40 of this specification, and in which—

Figure 1 is a substantially central vertical section through the valve on the line 1 1 of Fig. 2. Fig. 2 is a horizontal section on the line 2 2 of Fig. 1, looking down. Fig. 3 is 45 a substantially central vertical section showing a slightly-different form; and Fig. 4 is a horizontal section on the line 4 4 of Fig. 3, looking down.

Like letters of reference indicate like parts 50 throughout the several views.

Referring now to the details of the drawings by letter, A designates the valve casing

or chamber, having a tubular extension A', through which the valve-stem works, and the upper end of which is guided in the bore b 55 of the cap B, as seen in Fig. 1, or in the screw-nut A⁵ in the form seen in Fig. 3. The tubular extension A' has near its upper end a lateral extension or nipple A², designed for attachment to or connection with the reservoir. 60 (Not shown.)

C is the cap or head to the valve-casing and held thereto by suitable bolts c, and between the inner face of this cap and the adjacent face of the body portion or casing is a gasket 65 D, of leather, rubber, or other suitable material, and extending to the opening E in the cap, which communicates with the interior of the casing and upon which the piston head or valve is designed to seat itself when the 70 pressure thereon is removed by the reduction of the pressure of the air in the train-pipe and serves to make a seat for the said piston or valve, so as to form a better joint and hold or retain the air in the water tank or 75 reservoir, as will be readily understood. The opening E is screw-threaded for connection with the main train-pipe or service-pipe of the train.

F is the valve or piston, of any suitable 80 material, preferably brass, provided with an annular groove f, in which is seated the packing-ring F', of any suitable or well-known form of construction. This piston-head or valve is mounted to reciprocate within the 85 cylinder or valve-chamber, which is provided with a bushing G, fitted therein and provided near its upper end with a vertical passage g of a length slightly greater than the thickness of the piston-head or valve, as seen in Fig. 1. 90 This valve or piston has a stem H, the upper portion of which is guided in the cap B or the adjusting-screw A⁵, as the case may be, while upon the upper face of the piston or valve is a boss I, the edge or periphery of which is 95 beveled upwardly, as seen at i, and in this edge are a plurality of grooves or channels J, as seen in both views, and which communicate with the space K between the upper face of the body portion of the valve or piston-head and the under face of the top of the valve chamber or cylinder, as seen in Fig. 1. 100 The conical boss or beveled portion I upon the upper face of the piston or valve engages

the inclined seat L in the top of the valve-chamber, as seen in Fig. 1, and limits the upward movement of the valve or piston, and the relative proportion and disposition of 5 parts is such as to prevent tight closing of the valve, so as to provide the space K just referred to.

With the parts constructed and arranged substantially as hereinbefore set forth the 10 operation is as follows, it being understood that the opening E is connected with the main train or service pipe and the nipple A² with the water tank or reservoir: The air entering through the opening E, acting upon 15 the under side of the piston or valve, forces the same upward, so that the passage g is disclosed or opened, and the air passes through the same into the space K above the piston or valve and through the passages J into 20 the chamber M of the vertical extension of the valve chamber or cylinder, and thence through the opening in the nipple A² into the water tank or reservoir. Now should the 25 air in the train-pipe be cut off or should there be a reduction in such pressure the valve will fall, so as to close the passage g, and thus prevent escape of the air that has already been accumulated in the tank. As soon as 30 normal pressure is again resumed in the main train-pipe or service-pipe the valve is forced upward and the air passes, as indicated by arrow, through the passage g into the space K and through the groove J into the chamber M and out through the passage in the nipple 35 A² to the reservoir. It will thus be seen that the device is automatic in its action, requiring no attention on the part of the attendant, and that sufficient pressure is at all times maintained within the water tank or reservoir. 40

In Figs. 3 and 4 we have shown another form of the invention in which the piston is designed to be near the bottom at all times, the bushing G being provided with the 45 passages g, as before, but which are disposed between the upper and lower edges thereof and extending for the greater portion of the height instead of being disposed near the top, as in the form shown in Fig. 1, and the grooves 50 J in the piston being omitted. The upper end of the piston-stem H is guided in the bore b of an adjusting-screw A⁵, having an annular shoulder a⁵, against which the end of the spring N is received, and this adjusting screw 55 or plug is screw-threaded and engages internal threads on the upper portion of the extension A' of the valve-casing. Its upper end

is polygonal or otherwise formed, as shown at a⁶, to receive a wrench or other tool by which it may be adjusted, and the cap A⁶ is 60 interiorly threaded to engage the exterior threads of this adjusting screw or plug. The operation is substantially the same as in the form illustrated in Figs. 1 and 2, except that the valve normally remains at the bottom and 65 the air passes through the vertical passages g around the piston and operates in substantially the same manner as the form hereinbefore explained.

Modifications in detail may be resorted to 70 without departing from the spirit of the invention or sacrificing any of its advantages.

In both Figs. 1 and 3 we have shown a spring N arranged around the valve-stem or the rod in the piston-head, and which serves to aid 75 the piston or valve in moving to its seat upon the reduction of pressure in the main train-pipe.

The adjusting-screw and form of cap illustrated in Fig. 3 may be employed in connection with the form of apparatus illustrated in Fig. 1 in lieu of the form of cap therein shown, if desired.

Having thus described our invention, what we claim as new, and desire to secure by Letters Patent, is—

1. The combination with the valve-chamber having a bushing with vertical groove, of a valve mounted to move in said chamber and having a stem, and a central boss, a cap on 90 the upper end of the chamber, and a spring around the stem of the valve acting upon the upper face of the latter; all substantially as herein shown and described.

2. The combination with the valve-chamber 95 and a bushing having vertical passages, of a piston mounted to move within the bushing, and a spring acting upon said piston and means for regulating the tension of said spring; substantially as described.

3. The combination with the valve-chamber and a bushing having vertical passages with a piston mounted to reciprocate therein, a cap, an adjusting-screw having a bore to guide the upper end of the piston-stem, and a spring 105 between said adjusting-screw and the piston; substantially as described.

In testimony whereof we affix our signatures in presence of two witnesses.

MICHAEL MAREA.
THOMAS CONNORS.
